UNITED STATES PATENT OFFICE

2,580,513

YARN TRAPPING AND SEVERING MEANS
FOR CIRCULAR KNITTING MACHINES

Albert Matthews Brown, Leicester, England, assignor to G. Stibbe & Co. Limited, Leicester, England, a British company

Application September 2, 1950, Serial No. 183,037
In Great Britain September 27, 1949

7 Claims. (Cl. 66—140)

1

This invention relates to circular knitting machines, and has reference particularly to means employed in such machines for trapping and also severing yarns upon withdrawal from knitting.

Yarn trapping and severing means of the kind with which the invention is concerned comprise a fixed member and a relatively movable trapper jaw which co-operate to form a trapper, and, combined with the said trapper, a cutting device consisting of relatively movable cutter blades. Thus, a yarn withdrawn from knitting is severed, by the cutting device, from the fabric or article being knitted, and the loose end of the cut yarn extending from the yarn guide is disposed between the operative edge of the movable trapper jaw and the opposed surface of the aforesaid fixed member where it is trapped until again required for re-introduction to the needles of the machine for knitting.

Yarn trapping and severing means of this kind are designed for use in conjunction with yarn supplying mechanism including a plurality of yarn guides adapted to deal with respectively different yarns and to be operated selectively for the purpose of introducing desired yarns to, and withdrawing same from, the needles at predetermined times, according to requirements.

Moreover, the invention is applicable exclusively to circular knitting machines (more especially for the production of seamless hosiery) equipped with a welt mechanism comprising a dial with welt instruments or transfer bits in association with a dial cam system for co-operation with the needles in the production, automatically, of in-turned welts.

The object of the present invention is to provide, in a circular knitting machine furnished with yarn trapping and severing means of the kind concerned and welt mechanism as aforesaid, particularly simple and efficient means for actuating the cutting device.

Another object is to provide improved interconnected means for effecting conjoint operation of the trapper and the cutting device, as will be hereinafter described.

According to this invention one of the cams incorporated in the welt cam system or a part movable therewith is operatively connected with the cutting device and adapted normally to maintain the said device closed, and the means employed for rendering the said cam operative in the making of a welt are additionally operable at required times to move the cam or the associated part in such a way as to actuate the cutting device. This is made possible by reason of

2

the fact that the said welt cam and its actuating means (usually a lever operable from a control unit) have a certain amount of lost motion.

The particular cam used for rendering the welt instruments or transfer bits active at the commencement of knitting a welt may advantageously be operatively connected with the cutting device for the intended purpose.

In a convenient embodiment of the invention, 10 the cutting device comprises fixed and relatively movable blades arranged scissor fashion, the movable blade being secured to a spindle provided with a crank or an eccentric arranged to work in a slot or between guides in or on the welt cam concerned—or the aforementioned part movable therewith.

The relatively movable trapper jaw may be controlled in any conventional or other suitable manner independently of the cutting device. Preferably, however, the said jaw is controlled in

20 the manner described in my co-pending application No. 154,495, now abandoned, filed April 7, 1950. That is to say, the movable trapper jaw may be adapted to be normally pressed upon, and thereby locked in co-operative relationship with the fixed trapper member, by the same welt cam, or part movable therewith, from which the cutting device is actuated, this pressure upon the trapper jaw being relieved whenever the welt cam or associated part is moved to open the cutting device.

25 In this combined arrangement, therefore, the movable trapper jaw and the movable scissor blade are conjointly controlled from the same welt cam (or part combined therewith) in such a manner that the cutting device is opened to receive a yarn withdrawn from knitting simultaneously with relief of the pressure upon the movable trapper jaw and, conversely, the cutting device is closed to sever the withdrawn yarn consequent upon movement of the welt cam or associated part to lock the movable trapper jaw firmly in co-operative relationship with the opposed surface of the fixed trapper member.

30 In order that the invention may be more clearly understood and readily carried into practical effect, particular illustrative embodiments thereof applied to a circular seamless hose or like machine having a welt mechanism and equipped with a plurality of interchangeable yarn guides at a common feeding location will now be described with reference to the accompanying drawings, wherein,

35 Figure 1 is a general perspective view depicting the yarn trapping and severing means and 40 so much of the welt mechanism as is necessary

to illustrate the principle of the invention as embodied in one example thereof,

Figure 2 is a further general perspective view illustrating the preferred embodiment of the invention wherein the cutting device (shown closed) and the trapper are both controlled from a single welt cam,

Figure 3 is a similar perspective view to Figure 2 but with the cutting device shown open, and the levers for controlling the welt cams removed for the sake of clarity.

Figure 4 is a plan view of the said yarn trapping and severing means shown in relation to the latch ring and the interchangeable yarn guides of the machine,

Figure 5 is a part-sectional elevation as seen in the direction of the arrow A in Figure 4, that is to say from the front of the machine,

Figure 6 is a further part-sectional elevation as seen in the direction of the arrow B in Figure 4,

Figure 7 is a detail sectional view illustrating the cutting device, shown open, and the intermediate connections between the said device and the welt cam serving to control the same,

Figure 8 is a view similar to Figure 7 but the cutting device is closed,

Figure 9 is an "exploded" perspective view illustrating more clearly the component parts of the cutting device and of the connections between the same and the welt cam, and

Figure 10 is a plan view of the cam system whereby the welt instruments or transfer bits of the machine are operated and controlled.

Like parts are designated by similar reference characters throughout the drawings.

Referring to Figure 1, wherein the general principle of the invention is illustrated, it will be seen that the yarn trapping and severing means comprise a fixed member 1 and a pivoted trapper jaw 2 which co-operate to form a trapper T, and an associated cutting device C consisting of a fixed scissor blade 3 and a relatively movable scissor blade 4. In this particular example, the trapper T is controlled quite independently of the cutting device C, from a fulcrumed lever 5 one end of which is connected, through the medium of a link 6, with a tail portion 2a of the pivoted trapper jaw 2. The lever 5 is connectable with connections controlled from controlling or timing means such as a control drum (not shown) fitted with cams. Normally, the trapper jaw 2 is held in co-operative relationship with the fixed member 1, but whenever a yarn is withdrawn from knitting, the jaw 2 is first raised to open the trapper and so enable it to receive the said yarn and then lowered to trap and hold the latter. In accordance with the characteristic feature of the present invention, a welt cam 7, known as the "setting-up" cam, for rendering welt instruments or transfer bits active for the purpose of receiving loops from between alternate needles at commencement of knitting a welt, is employed for normally maintaining the cutting device C closed, and the conventional controlled lever 8 for operating the welt cam 7 is used for actuating the latter in such a manner as to raise the movable scissor blade 4 and so open the cutting device C at required times and conjointly with operation of the trapper T.

The cam 7, which is movable within a dial cam cap ring 9 and normally held up in an inoperative position clear of a dial carrying the welt instruments or transfer bits, is attached to a small carrier block 10 which is in turn secured to a tubular member 11 arranged for sliding move-

ment up and down on a vertical hollow post 12 containing a compression spring 13. At its upper end this spring bears upon the upper closed end of the tubular member 11. A lug 14 on the tubular member 11 is drilled through vertically for engagement with the shank of a fixed screw or pin 15 whereby the welt cam 7 is guided. The aforementioned lever 8 is for action upon the top of the upper closed end of the tubular member 11.

Now the cam 7 has lost motion in that it can be depressed a certain distance without affecting the welt instruments or transfer bits, and this fact is relied on for the purpose of the invention.

As will be seen the welt cam 7 is extended upwardly at 7a and has formed therein a horizontal

slot 16. Into this projects the cranked end 17a of a horizontally disposed spindle 17 mounted to turn in a bearing formed in a bracket 18 serving also to carry the fulcrumed trapper-controlling lever 5. The scissor blade 3 is fixed to the side of the bracket 18 remote from the trapper T. The spindle 17 projects through the fixed scissor blade 3 and has connected thereto the movable scissor blade 4. A compression spring 19 interposed between a collar 20 or flange on the spindle 17 and the opposing surface of the bracket 18 serves to hold the scissor blades together yieldingly.

Thus, whenever the spring-controlled tubular member 11 is depressed, as a consequence of suitable actuation of the lever 8, the cranked spindle will be turned to open the cutting device. Conversely, whenever the welt cam 7 is released and moves upwards under the spring action to its permitted extent, the cranked spindle 17 will be turned in the reverse direction to close the cutting device C. A few yarns which have been withdrawn from knitting and severed by the device C are indicated at Y.

The preferred embodiment of the invention, in which both the cutting device C and the trapper T are controlled from the same welt cam 7 will now be described with reference to Figures 2-10. This preferred embodiment is applied to a machine furnished with a plurality of interchangeable and selectively operable yarn guides such as 21 for supplying respectively different yarns Y to the needles (not shown). These guides, or feeders as they are often called, extend through a gap 22a formed in the conventional latch ring 22 (see Figure 4). In conjunction with the yarn guides 21 there is provided a common trapper comprising a fixed horizontal plate 23 carried by a central hub or boss 24, and a pivoted trapper jaw 25 which is disposed above the said plate and fulcrumed on a screw 26 in the hub or boss, the whole being located above a dial 27 (Figure 5) containing a circular series of welt instruments or transfer bits 28.

The welt instruments or transfer bits 28 are formed with upstanding actuating butts 28a and are thereby adapted to be operated and controlled by a cam system associated with a dial cam cap ring 29. As shown more clearly in Figure 10, the inner peripheral edge of the ring 29 is conventionally contoured for the purpose in view and, within the said ring, there are provided three vertically movable welt cams 7, 30 and 31 formed and arranged in known manner. The independently operable cam 7 is adapted, when depressed into its operative position, to act upon the actuating butts 28a seriatim and push all of the welt instruments or transfer bits 28 radially outwards, as permitted by the concave recess 29a formed in the dial cam cap ring 29, and so render the instruments or bits active at

the location **D** for the purpose of receiving loops from between alternate needles at the commencement of knitting a welt. The two cams **30** and **31**, on the other hand, are movable together and adapted, when both depressed into the path of the butts **28a**, to actuate the welt instruments or bits **28** suchwise as to effect transference of the retained loops back to the needles at the termination of the knitting of the welt.

The cam **7**, which is normally held up in an inoperative position clear of the dial **27**, is attached to a small carrier block **32** which is in turn secured to a tubular member **33** arranged, like the corresponding member in Figure 1, for sliding movement up and down on a vertical hollow post **34** containing a compression spring **35**. At its upper end this spring, as shown in Figure 5, bears upon the upper closed end of the tubular member **33**. The cam carrier block **32** is drilled through vertically for engagement with the shank **36a** of a fixed screw or pin **36** whereby it is guided. For depressing the member **33** and rendering the cam **7** operative at appropriate times, against the action of the compression spring **35**, there is provided a centrally pivoted lever **37** (Figure 2) the operative end **37a** of which bears upon the top of the upper closed end of the tubular member **33**. The lever **37** is actuated from the control drum of the machine (not shown) through the medium of a cam lever and an intermediate link.

The cams **30** and **31** are attached to a common carrier block **38** which is mounted and adapted to be operated and controlled in a similar manner to the carrier block **32**. That is to say, the block **38** is secured to a tubular member **39** arranged for sliding movement up and down a spring-controlled hollow post (not shown). The cam carrier block **38** is drilled for engagement with the shank of a fixed screw or pin such as **40** (Figure 4) whereby it is guided. A centrally pivoted lever **41**, actuated from the control drum, through the medium of a further cam lever and an intermediate link, is provided for action upon the tubular member **39**.

The cam carrier block **32** has lost motion in that it can be depressed a certain distance without affecting the welt instruments or transfer bits **28**. The tail end of the pivoted trapper jaw **25**—that is to say the end at the side of the fulcrum **26** remote from the trapping edge **25a** of the jaw—is provided with an extension or an equivalent formation such as **42** which is bent out of the plane of the jaw and into the path of the cam carrier block **32**. Accordingly, whenever the cam carrier block **32** is permitted to move upwards under the action of the compression spring **35**, the said block comes into contact with and presses upwards upon the underside of the tail extension or formation **42** as depicted in Figure 2, thereby forcing the operative edge **25a** of the trapper jaw **25** downwards and securely locking it in cooperative relationship with the fixed trapper plate **23**. To relieve the pressure, the conventional pivoted lever **37** is turned, without rendering the cam **7** operative, to an extent just sufficient to move the cam carrier or block **32** away from the tail extension or formation **42** on the jaw **25**, so releasing the latter. Special cams (i. e. cams not shown, additional to those necessary for operating the welt mechanism), are provided on the control drum for suitably actuating the pivoted lever **37** for relief of the pressure on the trapper jaw **25** at predetermined times. It is to be clearly understood, however, that when the pressure upon the movable trap-

per jaw **25** is relieved, the said jaw is not operated and separated from the fixed horizontal plate **23**; it merely remains where it is and acts under gravity to maintain at least some measure of control over the idle yarns already in the trapper. In short, the relief of pressure permits separation of the jaw **25** from the fixed plate **23** merely to the small extent necessary to permit of introduction into the trapper of a yarn withdrawn from knitting.

The welt cam **7** is extended upwardly at **7a** (as in the first described example) and has formed therein a short horizontal slot **16**. Into this slot projects the cranked end **43a** of a horizontally disposed spindle **43**, which is mounted to turn in a tubular bearing (see Figure 9) fixed in a bracket **45** secured to the central hub or boss **24**. Secured by a screw **46** to the side of the bracket **45** remote from the movable trapper jaw **25** is one scissor blade **47** of a cutting device. The operative portion **47a** of the fixed blade **47** extends outwardly from the bracket **45**—immediately above the fixed horizontal plate **23**. As shown in Figure 9, the fixed scissor blade **47** is also provided with an integral upstanding portion **47b** in which is formed a hole **48** adapted to receive the appropriate end of the tubular bearing **44** projecting slightly from the bracket **45**. In this way the projecting end of the said bearing serves to locate the fixed scissor blade in position. The spindle **43** projects right through the tubular bearing **44** and has clamped upon its end a member **49** to which a movable scissor blade **50** is secured by a screw **51**. To prevent it turning on the member **49**, the scissor blade **50** has formed therein a hole **52** (Figure 9) through which the spindle **43** extends. Accordingly, whenever the spindle **43** is turned, the movable scissor blade **50** will turn with it. Adjacent to its cranked portion **43a** the spindle **43** has fitted thereon a collar **53**, or is flanged, and there is interposed between the collar or flange and the bracket **45** a compression spring **54** which surrounds the tubular bearing **44** and serves to hold together the scissor blades **47** and **50** yieldingly. The construction and arrangement are therefore such that whenever the welt cam **7** is depressed, not only will the pressure on the pivoted trapper jaw **25** be relieved, but the cranked spindle **43** will be turned to raise the scissor blade **50** and so open the cutting device. Conversely, whenever the welt cam **7** is released and permitted to move upwardly, the operative edge **25a** of the trapper jaw **25** will be forced downwards and locked in co-operative relationship with the fixed trapper plate **23**, and the spindle **43** will be simultaneously turned in the reverse direction to close the cutting device.

In a multiple trapper unit, that is to say a unit comprising a main trapper and cutter and auxiliary trappers and cutters, the construction herein described may apply to either or all of such trappers and cutters.

What I claim then is:

1. In a circular knitting machine, in combination, yarn trapping means consisting of a fixed member and a relatively movable trapper jaw adapted to trap and hold between them a yarn withdrawn from knitting, an associated cutting device comprising relatively movable scissor blades for severing a withdrawn yarn, a welt mechanism comprising a dial equipped with welt instruments and cams for actuating the said instruments in the production of welts, means which operatively connect a selected one of the welt cams with the cutting device and are adapted

normally to maintain the said device closed, and means adapted not only to render the said welt cam operative in the making of a welt but also to move the said cam at required times suchwise as to actuate the cutting device.

2. In a circular knitting machine, in combination, yarn trapping means consisting of a fixed member and a relatively movable trapper jaw adapted to trap and hold between them a yarn withdrawn from knitting, an associated cutting device comprising relatively movable scissor blades for severing a withdrawn yarn, a welt mechanism comprising a dial equipped with welt instruments and cams for actuating the said instruments in the production of welts, including a setting-up cam for rendering the instruments active at the commencement of knitting a welt, means which operatively connect the said setting-up cam with the cutting device and are adapted normally to maintain the said device closed, a controlled lever adapted not only to render the setting-up cam operative in the making of a welt but also to move the said cam at required times suchwise as to actuate the cutting device.

3. In a circular knitting machine, in combination, yarn trapping means consisting of a fixed member and a relatively movable trapper jaw adapted to trap and hold between them a yarn withdrawn from knitting, an associated cutting device comprising fixed and relatively movable blades arranged scissor fashion for severing a withdrawn yarn, a turnable spindle with which the movable scissor blade is connected so as to turn therewith, the end of the said spindle remote from the cutting device being cranked, a welt mechanism comprising a dial equipped with welt instruments and cams for actuating the said instruments in the production of welts, a selected one of the welt cams having therein a slot in which the cranked end of the aforesaid spindle is engaged so that there is an operative connection between the said welt cam and the cutting device which connection serves normally to maintain the cutting device closed, and means adapted not only to render the said welt cam operative in the making of a welt but also to move the cam at required times suchwise as to device.

4. In a circular knitting machine, in combination, a welt mechanism comprising a dial equipped with welt instruments and cams for actuating the said instruments in the production of welts, yarn trapping means consisting of a fixed member and a relatively movable trapper jaw adapted to trap and hold between them a yarn withdrawn from knitting, a part which carries a selected one of the welt cams and is arranged normally to press on a formation on the movable trapper jaw so as normally to lock the latter in co-operative relationship with the fixed member of the trapper, a cutting device comprising relatively movable scissor blades for severing a withdrawn yarn, means which operatively connect the aforesaid selected welt cam with the cutting device and are adapted normally to maintain the latter closed, and means adapted

not only to render the said welt cam operative in the making of a welt but also to move the said cam at required times suchwise as to relieve the pressure on and thereby release the movable trapper jaw conjointly with opening of the cutting device.

5 movable trapper jaw conjointly with opening of the cutting device.

5. A combination according to claim 1, where-
in the selected welt cam is mounted on a guided
and spring-controlled carrier block which is nor-
mally urged by the spring means to hold the cam
10 inoperative and the cutting device closed.

Inoperative and the cutting device closed.

6. In a circular knitting machine, in combination, a welt mechanism comprising a dial equipped with welt instruments and cams for actuating the welt instruments in the production of welts, including a setting-up cam for rendering the instruments active at the commencement of knitting a welt and the said setting-up cam having a slotted extension, a guided and spring-controlled carrier block upon which the setting-up cam is mounted and by which the said cam is normally held inoperative, yarn trapping means consisting of a fixed member and a pivoted trapper jaw adapted to trap and hold between them a yarn withdrawn from knitting, the tail end of the said pivoted jaw having an extension disposed in the path of the aforesaid cam carrier block so that whenever the latter is permitted to move under the spring action it comes into contact with and presses upon the tail extension of the pivoted trapper jaw thereby locking the latter in co-operative relationship with the fixed trapper member, a cutting device comprising fixed and relatively movable blades arranged scissor fashion for severing a withdrawn yarn, a turnable spindle with which the movable scissor blade is connected so as to turn therewith, the end of the said spindle remote from the cutting device being cranked and engaged in the slot formed in the extension of the setting-up cam so that there is an operative connection between the said cam and the cutting device which connection serves normally to maintain the cutting device closed, and means adapted not only to render the setting-up cam operative in the making of a welt but also to move the said cam at required times suchwise as to relieve the pressure on and thereby release the movable trapper jaw conjointly with opening of the cutting device.

50 7. A combination according to claim 3, where-
the spindle is mounted to turn in a fixed bracket
and is provided with a flange between which
and the said fixed bracket is interposed a com-
pression spring serving to hold together yielding-
55 ly the blades of the cutting device.
